CLAIM

The ornamental design for a ball holder, as shown and described.

DESCRIPTION

FIG. 1 is a front perspective view of the design;

FIG. 2 is a front view;

FIG. 3 is a top plan view;

FIG. 4 is a rear view;

FIG. 5 is a bottom plan view;

FIG. 6 is a left side view;

FIG. 7 is a right side view; and,

FIG. 8 is a front perspective view of the ball holder, wherein the broken line showing of the ball is for illustrative purposes only and forms no part of the claimed design.
